UNITED STATES PATENT OFFICE.

SAMUEL TRUAN HOAR, OF MEADERVILLE, MONTANA, ASSIGNOR OF ONE-HALF TO
JAMES DONER, OF BUTTE, MONTANA.

POWER SHOVEL.

Application filed February 17, 1923. Serial No. 619,613.

To all whom it may concern:

Be it known that I, SAMUEL T. HOAR, a citizen of the United States, residing at Meaderville, county of Silver Bow, and 5 State of Montana, have invented certain new and useful Improvements in a Power Shovel, of which the following is a specification.

My invention relates to power shovels and 10 particularly to such shovels especially designed for use in mines.

On account of the narrow passageways and restricted spaces in mines, power shovels of ordinary construction are not adapted 15 for use therein.

The object of my invention is to provide a power shovel of such construction that it may be readily moved from level to level in mines, pass the chutes and through the 20 various mine galleries; and which shall be sufficiently flexible to work rapidly and freely in the restricted spaces usually occurring in mines. A further object of my invention is to provide a device of the kind 25 mentioned which may be operated to clear the ground from close to the device, to the full reach of the shovel; and which may be operated to readily clear obstructions which resist its power. A further object of my 30 invention is to provide a device as mentioned with means for clamping the same in position during operation. Other objects will appear hereinafter.

With these objects in view, my invention 35 consists generally in a truck mounted upon wheels, a body rotatably mounted thereon, a cross-head slidably mounted on said body, and carrying a pair of drums and means for operating the same, an arm 40 hingedly connected at one end to said cross-head and having a pair of parallel angularly disposed extensions, a scoop lever pivotally mounted between said extensions, and a scoop on said lever, said arm and said lever 45 being connected by cables to said drums respectively. My invention further consists in a device as mentioned in which the scoop lever is adjustably connected to said extensions. My invention further consists 50 in a device as mentioned in combination with means for moving said cross-head on said body and means for rotating said body. My invention further consists in a device as mentioned in which the length and breadth of

the truck and the body are of minimum 55 size, to permit the device to be accommodated in a mine cage for moving it from level to level, and to permit it to pass through the mine galleries, in combination with lateral extensions for the table of the 60 truck to support the body when rotated. My invention further consists in a device as mentioned adapted to run on the mine tracks and further characterized by means for clamping the device to the rails. My in- 65 vention further consists in various details of construction and arrangements of parts all as will be fully described hereinafter and particularly pointed out in the claims.

My invention will be more readily understood by reference to the accompanying drawings forming a part of this specification and in which—

Fig. 1 is a side elevation of a power shovel 70 embodying my invention,

Fig. 2 is a plan view thereof,

Fig. 3 is a vertical transverse section on the line 3—3 of Fig. 1,

Fig. 4 is a side elevation with parts removed and scoop raised to enter mine cage 80 and to pass through galleries, and

Fig. 5 is a rear end view of same.

Referring now to the drawings, 1 indicates the table of a truck from which depend side frames 2, provided with boxes or bearings 3 for axles 4 of the wheels 5, said wheels being adapted to run on the rails A of the mine tracks. The table 1 projects a slight distance laterally beyond the side frames 2, and to these projecting edges are 90 secured extensions 6 which form a continuation of the table to support the superimposed parts when the body is swinging laterally in use as hereinafter described. These extensions are provided with depending plate portions 7 at their inner edges which rest against and may be secured to the side frames 2. Preferably, these plates 7 are provided with bearings 8 to rest on the projecting ends of the axles 4, and brackets 9 may be provided for further strengthening the extensions 6. The extensions 6 are detachably secured to the truck for reasons which will appear hereinafter.

Rotatably mounted on the truck is the 105 body which may be of any preferred construction, but comprises a bottom 11, sides 12 and a rear end plate 13. A king bolt

14 passes through the centers of the bottom 11 and truck table 1, and concentric therewith is a large gear 15 fixed to the truck. Meshing with said gear is a pinion 16 having a vertical shaft extending through the bottom of the body and driven by a reversible rotary engine 17. This may be of any desired type and I have therefore illustrated the same but conventionally. 18 indicates 19 a control lever for the engine 17 arranged adjacent the seat 19 for the operator.

Longitudinally slidable within the body is a cross-head comprising an engine bed plate 20, side walls 21 and a rear end wall 22. The 15 edges of the plate 20 project beyond the walls 21 and are arranged between guides secured to the walls 12. These guides may consist of angle irons 31, as shown in the drawings. Extending longitudinally of the 20 body below the bed plate 20, of the cross head, is a screw shaft 23, one end of which projects through the rear wall 13 of the body, and is provided with a sprocket gear 24 connected by a chain 25 to a gear 26 on a shaft 27 driven by an engine 28. The 25 engine 28 is of the reversible type similar to engine 17, and is controlled by a lever 29 which is also within easy reach from the seat 19. Secured to the engine bed plate 30 is a depending lug 30 through which the screw 23 is threaded. It is evident that by means 35 of the engine 28 the engine bed plate may be moved forwardly or backwardly as desired. It will be noted that the guides 31 are at a sufficient height for the cross-head to fully clear the engines 17 and 28.

Hingedly connected to the forward end 40 of the cross-head is an angle frame for supporting the scoop lever. This frame comprises an arm 32 hingedly connected at its rear end to the cross-head, as at 33, and a pair of parallel members 34, 34 secured to the outer end thereof. The arm 32 is at substantially right angles to the members 34 and preferably secured to the same at about 45 midway of their length, forming a T-shaped structure. This may be built up of such structural elements as are found desirable, but in the drawings I have illustrated the 50 arm 32 formed of two spaced angle bars 35—35 connected by a plate 36. The rear ends of the bars 35 project beyond the plate 36 and are provided with eyes to receive a cross rod 37 fixed to the cross-head. The members 34 may be channel irons secured to the bars 35 by plates 38, and spaced apart 55 by a plate 39, or equivalent elements, above the arm 32. This leaves the space between the lower portions of the members 34 open and free to permit free swinging of the scoop 60 and scoop lever between them, as will appear hereinafter. 40 indicates the scoop which is rigidly fixed between two parallel bars 41—41, the upper ends of which are connected 65 by a cross bar 42. The structure thus

formed by the bars 41 and scoop 40 fits between the bars 34 and is pivotally connected thereto as by bolts 43. The bars 34 of the angle frame and the bars 41 forming the 70 scoop lever are provided with a series of holes 44 and 45 respectively, for the bolts 43, thereby providing means for adjustment of the scoop with relation to angle frame to adapt the device to various conditions of work. The scoop is provided with the usual hinged bottom 46 releasably held in position by a latch 47 controlled by a cable 48 extending to a point adjacent the seat 19.

Rotatably mounted in the said cross-head, as between the walls 21, is a pair of cable drums 49 and 50 which are driven by reversible engines 51 and 52 respectively, through sprocket gearing 53 and 54. 55 and 56 indicate the control levers for the engines 51 and 52, said levers being also arranged adjacent the seat 19. A cable 57 is wound on the drum 49 and is attached to the upper end of the angle frame lever as at 58; and a similar cable 59 wound on the drum 50 extends over a roller 60 on said angle frame and is connected to the member 42 of the scoop frame. It is obvious that, as the engines may be independently operated and controlled, that the angle frame and the scoop frame may be independently 95 actuated.

The several engines contained within the device may be of any desired kind and are indicated but conventionally as fluid operated, reversible motors. To this end a pipe 61 is provided in the body connected to the engines 17 and 28. This pipe extends through the back of the body and is connected to a flexible supply pipe 62. A pipe 63 arranged in the cross-head supplies the engines 51 and 52, and this is connected by a flexible section 64 to the pipe 61. All the engines are thus supplied from same source; and it will be noted from the above description that the control levers for all the engines are within reach from the seat 19; hence the operation of the entire device is under the control of a single operator.

The device above described is small and comparatively light; and in order to hold the same in position and resist the reaction from the force applied to the scoop, means must be provided for holding the device in position during operation. To this end I provide means for clamping the device to the rails. This comprises a pair of shoes 65 bearing against the outer faces of the rails A, and a bolt 66 for clamping the shoes against the rails. The shoes are of any desired form but may be constructed of rails, inverted, and swingingly supported from the side frames; a supporting plate 67 being hinged to the side frames as at 68 and having the shoe or rail section 65 attached to its lower edge. The bolt 66 extends through 125

the apertures in the plates 67, and followers 69 are provided between the shoes and the head and nut of the bolt respectively, as shown, to transmit the force directly to the shoes. To prevent bending the rails A and to form a more secure clamp, a spacing member 70 is suspended from the bolt 66, the ends of which engage the inner faces of the rails A.

10 The operation of the device is as follows: To facilitate the transporting of the shovel into the mine, the lateral truck extensions 6 are removed as is also the seat 19 and associated foot rest. The scoop and operating 15 arms are folded back upon the cross-head as shown in Figs. 4 and 5. If desired the bolt 66 and attached parts may also be removed. The device will then occupy a space but the length and breadth of the truck table 1 and 20 will be readily accommodated on the mine cage for lowering to the level where it is to be operated. The wheels 5 fit on the mine tracks and the shovel may be transported thereon through the galleries. When the device 25 has reached the location where it is to operate, the lateral extensions 6 are secured in position, and also the seat 19. If the bolt 66 has been removed, it is inserted in place, together with the spacer 70 and followers 69. The bolt is then tightened to clamp the 30 device to the rails A.

The engine 28 is then operated to move the cross-head a short distance forwardly and the scoop and actuating frames are lowered into operative position, such as 35 shown in Fig. 1. By manipulating the cables 59 and 57 the scoop 40 may be made to lift a quantity of material into elevated position. The cross-head is then retracted to lessen the radius of swing of the scoop, and the body rotated by engine 17 through 40 approximately 180°. The cross-head is again projected, which moves the scoop above a car on the track A behind the device and the scoop is discharged by releasing the latch 45 47 by cable 48. The cross-head is again retracted and the body swung into operative position, and the operation repeated. Should the scoop encounter a resistance 50 greater than its ability to overcome, it is evident that it may be cleared by a manipu-

lation of the hinged frames and the cross-head.

I claim:

1. In a device of the class described a 55 truck mounted upon wheels, a body rotatably mounted thereon, a cross-head slidably mounted on said body, an arm hingedly connected at one end to said cross-head and having a pair of parallel angularly disposed 60 extensions, a scoop lever pivotally mounted between said extensions, a scoop on said lever, a pair of drums on said cross-head connected to said arm and said lever respectively, and means for operating said drums 65 independently.

2. A device as set forth in claim 1, further characterized by means for moving said cross-head longitudinally of the body and means for rotating said body, substantially 70 as described.

3. A device as set forth in claim 1 in combination with a screw shaft arranged longitudinally of the body, a lug fixed to said cross-head and in threaded engagement with 75 said screw, and means for operating said screw, substantially as described.

4. A device as set forth in claim 1, in which said body is of substantially the same length and breadth as said truck, in combination with lateral extensions for said truck detachably mounted thereon, substantially 80 as described.

5. A device as set forth in claim 1 in which said extensions are at substantially 85 right angles to the arm and project both above and below the latter, cables connecting the drums with the arm and lever respectively, and a guide for the scoop lever cable at the upper end of said extensions, 90 substantially as described.

6. A device as set forth in claim 1 further characterized by means for adjustably connecting the scoop lever to said extensions, substantially as described. 95

In testimony whereof I have signed my name to this specification in the presence of two subscribing witnesses.

SAMUEL TRUAN HOAR.
